HORN CONTROL CIRCUIT

Joe White, Anderson, and John W. Falconer, Mid-dletown, Ind., assignors to General Motors Corporation, Detroit, Mich., a corporation of Delaware

Application May 26, 1939, Serial No. 275,895

11 Claims. (Cl. 177—7)

This invention relates to systems of controlling automobile horns and more particularly to systems including a low volume horn for city driving and a high volume horn for country or high speed driving.

It is the object of the present invention to provide a system of control in which the pressing of the horn button causes a low volume horn to sound in normal city driving but which will cause the high volume horn to sound also if the horn button is pressed at a time when the hydraulic brakes are applied. The system provides for sounding the high volume horn as well as the low volume horn when the horn button is pressed at a time when the vehicle speed exceeds a limit prescribed for city driving for example a speed in excess of 35 M. P. H.

Further objects and advantages of the present invention will be apparent from the following description, reference being had to the accompanying drawing wherein a preferred embodiment of the present invention is clearly shown.

In the drawing:

Figs. 1, 2, 3 and 4 are diagrams of various embodiments of the present invention.

Referring to Fig. 1 numeral 20 designates the low volume horn and 21 the high volume horn. One terminal of the low volume horn 20 is grounded and the other terminal is connected by wire 22 with relay contact 23 which is normally out of engagement with contact 24 carried by armature 25 connected by wire 26 with battery 27 which is grounded. Wire 26 is connected with relay magnet winding 30 connected by wire 31 with horn switch stationary contact 32 which may be bridged by horn button contact 33 with horn button stationary contact 34 which is grounded. When horn button 33 is pressed to connect contacts 32 and 34 relay winding 30 is energized and armature 25 is attracted thereby moving contact 24 into engagement with contact 23 in order to connect low volume horn 20 with battery 27. These are the circuits which are established during normal city driving.

The action of the system is modified by circuit established thru the stop light switch 40 labeled "S. L. S." Switch 40 comprises a fluid pressure chamber provided by a housing 41 closed by a flexible diaphragm 42 capable of moving a contact 43 into engagement with stationary contacts 44 and 45. Contact 44 is connected with the battery by a wire 46, contact 45 is connected by a wire 47 with grounded stop lamp 48. Wire 47 is connected by wire 50 with relay magnet winding 51 which is grounded and which is also

connected with relay armature 52 carrying contact 53 normally out of engagement with relay contact 54. Contact 54 is connected by wires 55 and 56 with one terminal of high volume horn 21 having its other terminal connected by wire 57 with wire 22. When the brakes are applied the pressure developed in the hydraulic braking system causes the diaphragm 42 to move downwardly in Fig. 1 in order to move contact 43 into engagement with contacts 44 and 45 to cause the stop signal 48 to burn and to cause the relay winding 51 to be energized. When this occurs the armature 52 is attracted in order to close contacts 53 and 54. Therefore, when the horn button 33 is pressed at the time when the brakes are applied, the following circuit will be established between the battery 27 and the high volume horn 21; battery 27, wire 26, armature 25, contact 24, contact 23, wire 22, wire 57, high volume horn 21, wires 56 and 55, contacts 54 and 53, and grounded armature 52. Therefore the high volume horn 21 will sound simultaneously with the sounding of the low volume horn 20, when the horn button 33 is pressed at a time when the brakes are applied.

At speeds above 35 M. P. H. the circuit of the high volume horn is completed independently of operation of the hydraulic brake system by means of an air switch comprising a grounded vane contact 60 movable into engagement with contact 61 connected with wire 56. Arrow 62 indicates the direction of air current induced by the engine cooling fan 63. At a speed above a prescribed limit, for example 35 M. P. H., the vane 60 will engage the contact 61 to complete the high volume horn circuit at the time the button 33 is pressed so that, when driving at higher speeds generally attained when driving in the country, the high volume horn as well as the low volume horn will be sounded whenever the horn button is pressed.

Fig. 2 shows a modification of the system shown in Fig. 1 in which only one relay is used but a separate hydraulic switch is required since the regular stop light switch cannot be used in a single relay circuit. In Fig. 2 the battery 27 is connected by wires 70 and 71 with one terminal of the low volume horn 20 the other terminal of which is connected by wires 72 with the horn switch contact 32. When horn button 33 is pressed during ordinary city driving the low volume horn 20 will sound since it is directly connected with the battery 27. The high volume horn 21 has one terminal grounded and the other connected by wire 73 with relay contact

74 normally out of engagement with a contact 75 carried by armature 76 which is connected with wire 70 and with relay magnet winding 77. Winding 77 is connected by wire 78 with contact 79 of a hydraulic switch which includes a diaphragm 80 carrying a contact 81 normally out of engagement with contact 79 and a second stationary contact 82 connected by wire 83 with wire 72. When the brakes are applied the separate hydraulic switch including the diaphragm 80 completes the circuit by the engagement of contact 81 with contact 79 and 82 thereby connecting relay winding 77 with the battery at the time the button 33 is pressed. This circuit includes battery 27, wire 70, winding 77, wire 78, contacts 79, 81 and 82, wire 83, wire 72, contacts 32, 33 and 34. When this circuit is completed by the closing of the hydraulic switch contacts 79, 81 and 82 and by the closing of the horn switch contacts 32, 33 and 34, the magnet coil 77 will be energized and armature 76 will be attracted and contacts 75 and 74 will be closed to connect the high volume horn with the battery 27 so that it will sound simultaneously with low horn 20. Thus both horns will sound when the brakes are applied and the horn switch is closed. This system of Fig. 2 includes the air switch comprising air vane 60 and contact 61. In Fig. 2 contact 61 is connected by wire 85 with wire 78 and vane 60 is connected by wire 86 with wire 72. At a speed above 35 M. P. H. for example, the air vane 60 engages the contact 61 so that, if the horn button is pressed, the circuit of relay winding 77 will be completed thru the air switch and the horn switch regardless of the application of brakes which would close the auxiliary hydraulic switch. Therefore it is apparent that both horns will be sounded when the horn button 33 is pressed at speeds above 35 M. P. H. regardless of the application of hydraulic brakes.

Fig. 3 embodies a combination of some of the circuits of Figs. 1 and 2. The current for the low volume horn 20 passes through the horn button switch as in Fig. 2. The stop light switch 40 controls the energization of relay magnet winding 51 as in Fig. 1. The relay magnet winding 77 of Fig. 2 is connected in Fig. 3 across line wires 70 and 72 so that this relay winding is energized every time the horn button 33 is closed. Winding 77 is connected by wire 90 to wire 72. Wire 91 connects relay stationary contact 74 with relay armature 52. Wire 92 connects wire 91 with air switch vane 60. Wire 93 connects air switch contact 61 with wire 94 which connects high volume horn 21 with contact 54.

When the horn button 33 is closed in the circuit shown in Fig. 3, the low volume horn 20 will sound and winding 77 will be energized and contact 75 will engage contact 74. The circuit to the high volume horn 21 will be closed at this time provided contacts 53 and 54 are closed as the result of energization of relay winding 51 which will occur if the stop light switch 40 is closed as a result of the application of the hydraulic brakes. When the horn button 33 is closed at the time the brakes are applied the circuit of the high volume horn 21 shown in Fig. 3 will be as follows: battery 27, wire 70, the armature 52, contacts 53 and 54, wire 94, horn 21. At speeds above a certain speed, such as 35 M. P. H., the air switch vane contact 60 will engage contact 61 to complete the horn circuit independently of the closing of the stop light 75

switch 40. This circuit will include battery 27, wire 70, armature 76, contacts 75 and 74, wire 92, air switch contacts 60 and 61, wire 93, wire 94 and horn 21.

5 The system shown in Fig. 4 embodies the features of Fig. 1 and adds a relay, in order to avoid passing current to the high volume horn directly through the air switch. This additional relay in Fig. 4 comprises a magnet winding 101 connected by wire 100 with wire 55 and with air switch contact 61, and also connected with wire 102 which connects wire 22 with relay armature 103 carrying contact 104 which is normally out of engagement with contact 105 connected by wire 106 with high volume horn 21. In Fig. 4 the circuit of relay magnet winding 101 is completed, provided horn button 33 has been pressed to effect through the energization of relay winding 30 the closing of contacts 23 and 24, and provided the stop light switch 40 is closed to effect through the energization of relay 51 the closing of contacts 53 and 54, or provided the air switch contacts 60 and 61 are closed in response to the attainment of speeds in excess of 35 M. P. H. for example. The energization of relay coil 101 effects the attraction of armature 103 and the closing of contacts 104 and 105 to complete the high volume horn circuit comprising, battery 27, wire 26, armature 25, contacts 24 and 23, wire 22, wire 102, armature 103, contacts 104, and 105, wire 106, and horn 21. Therefore, in the system shown in Fig. 4 the relays which include, respectively, the windings 30 and 101, carry all the horn operating currents. The only current carried by the air vane switch is that required to energize winding 101.

As in the systems shown in Figs. 1, 2 and 3, the system shown in Fig. 4 provides for the operation of the high volume horn as well as the low volume horn at any time when the driving speed exceeds a predetermined value, such as 35 M. P. H., or whenever the brakes are applied. In addition to brake switch control and the air switch control provided for in the other figures, Fig. 4 provides also for control by a switch responsive to the acceleration of the vehicle in traffic. This control comprises a stationary contact 110 connected with wire 100, a stationary grounded contact 111 and a movable bridging contact 112 normally held by a spring 113 out of engagement with contacts 110 and 111. Contact 112 is operated by a rod 114 located in the path of movement of the accelerator pedal 115. When the vehicle is accelerated in traffic the pedal 115 engages the rod 114 and closes the contacts 110, 111, and 112 so that horn 21 will sound when the horn button 33 is pressed.

60 Any form of brake controlled switch may be substituted for the pressure fluid switch shown, such as a mechanically operated switch operated by the brake pedal.

65 While in the specification and claims we have used the terms "low volume horn" and "high volume horn," it will be understood that the present invention embraces any combination of horns or other signal devices which gives two distinct signals, one for city driving and the other for country driving. For example, the automobile may be equipped with two horns of about the same volume but differing in pitch. The horn of lower pitch could be sounded alone for the city signal and both horns together for the country signal, or a pair of horns could be sounded together for the country signal and a separate single horn for the city signal.

While the embodiment of the present invention as herein disclosed constitutes a preferred form, it is to be understood that other forms might be adopted, all coming within the scope of the claims which follow.

What is claimed is as follows:

1. A horn control system for automobiles comprising a current source, a series circuit comprising the current source, a manually controlled switch and a low volume horn, a circuit in series with the manually controlled switch and in parallel with the low volume horn and comprising a pair of normally open relay contacts and a high volume horn and a second circuit in series with the manually controlled switch and in parallel with the low volume horn and comprising an electromagnet coil for closing the relay contacts and a normally open switch closed automatically in response to a condition of vehicle operation.
2. A system of control for automobile horns comprising a current source, a low volume horn, a high volume horn, a manually controlled switch for connecting the low volume horn with the source, an automatically operated, normally open circuit making means in series with the high volume horn and both in a circuit paralleling the low volume horn, electromagnetic means for causing said circuit making means to make a connection in said paralleling circuit, and means for connecting the source with said electromagnetic means and including a switch closed in response to the application of the vehicle brakes.
3. A system of control for automobile horns comprising a current source, a low volume horn, a high volume horn, a manually controlled switch for connecting the low volume horn with the source, an automatically operated, normally open circuit making means in series with the high volume horn and both in a circuit paralleling the low volume horn, a switch connected with the source and closed in response to the application of the vehicle brakes, parallel circuits connected by said switch with the source, one of said circuits including a signal lamp to indicate application of brakes, the other of said circuits including an electromagnet for causing said automatically operated circuit making means to make a connection in the circuit of the high volume horn.
4. A system of control for automobile horns comprising a current source, a low volume horn, a high volume horn, a manually controlled switch for connecting the low volume horn with the source, an automatically operated, normally open circuit making means in series with the high volume horn and both in a circuit paralleling the low volume horn, a second circuit paralleling the low volume horn and connected with the source through said manually controlled switch and including an electromagnet for closing the circuit making means of the high volume horn circuit and including a switch closed in response to the application of the vehicle brakes.
5. A system of control for automobile horns comprising a current source, a low volume horn, a high volume horn, a manually controlled switch for connecting the low volume horn with the source, a circuit paralleling the low volume horn and including the high volume horn and connected with two branch circuits leading to the current source, a switch in one branch for completing a connection between the source and high volume horn when a certain vehicle speed has been attained and provided the manually controlled switch is closed, a pair of switch contacts in the other branch, an electromagnet for closing said switch contacts, a signal lamp in parallel with said electromagnet, and a switch closed in response to the application of the vehicle brakes for connecting the source with the lamp and electromagnet.
6. A system of control for automobile horns comprising a current source, a low volume horn, a high volume horn, a manually operated switch for connecting the low volume horn with the source, a circuit paralleling the low volume horn and including, in series, two pairs of switch contacts and the high volume horn, an electromagnet for closing one of said pairs of contacts and connected with the source through said manually operated switch, a second electromagnet for closing the other of said pairs of contacts, a signal lamp in parallel with said second electromagnet, and a switch closed in response to the application of the vehicle brakes for connecting the source with the lamp and the second electromagnet.
7. A system of control for automobile horns comprising a current source, a low volume horn, a high volume horn, a manually operated switch for connecting the low volume horn with the source, a circuit paralleling the low volume horn and including, in series, two pairs of switch contacts and the high volume horn, an electromagnet for closing one of said pairs of contacts and connected with the source through said manually operated switch, and means responsive to the application of vehicle brakes for closing the second pair of contacts.
8. A system of control for automobile horns comprising a current source, a low volume horn, a high volume horn, a manually operated switch for connecting the low volume horn with the source, a circuit paralleling the low volume horn and including, in series, two pairs of switch contacts and the high volume horn, an electromagnet for closing one of said pairs of contacts and connected with the source through said manually operated switch, means responsive to the application of vehicle brakes for closing the second pair of contacts, and a switch for bypassing the second pair of contacts when a certain vehicle speed has been attained.
9. A system of control for automobile horns comprising a current source, a low volume horn, a high volume horn, a manually controlled switch connected with the source, three parallel circuits connected with the source through said manually controlled switch, one circuit including the low volume horn, another circuit including the high volume horn and a pair of contacts in series, and another circuit including an electromagnet for closing said pair of contacts and a second pair of switch contacts, a second electromagnet for closing said last mentioned pair of contacts, a signal lamp in parallel with said second electromagnet, and a switch closed in response to the application of the vehicle brakes for connecting the source with the lamp and the second electromagnet.
10. A system of control for automobile horns comprising a current source, a low volume horn, a high volume horn, a manually controlled switch for connecting the low volume horn with the source, an automatically operated, normally open circuit making means in series with the high volume horn and both in a circuit paralleling the low volume horn, electromagnetic means for causing said circuit making means to make a connection

nection in said paralleling circuit, and means for connecting the source with said electromagnetic means and including a switch closed in response to depression of the accelerator pedal to an extent required for acceleration of the vehicle in traffic.

11. A system of control for automobile horns comprising a current source, a low volume horn, a high volume horn, a manually controlled switch for connecting the low volume horn with the source, an automatically operated, normally open circuit making means in series with the high volume horn and both in a circuit paralleling the

5 low volume horn, electromagnetic means for causing said circuit making means to make a connection in said paralleling circuit and means for connecting the source with said electromagnetic means and including a switch closed in response to depression of the accelerator pedal to an extent required for acceleration of the vehicle in traffic, and a switch for by-passing the last mentioned switch when a certain vehicle speed 10 has been attained.
